FEED MECHANISM FOR MACHINE TOOLS

Filed Oct. 15, 1919

Inventor:
Alfred Trosch
by Clyde L Rogers
his Atty.

UNITED STATES PATENT OFFICE.

ALFRED TROSCH, OF ROCHESTER, NEW YORK, ASSIGNOR TO ARTHUR H. INGLE, OF ROCHESTER, NEW YORK.

FEED MECHANISM FOR MACHINE TOOLS.

Application filed October 15, 1919. Serial No. 330,816.

To all whom it may concern:

Be it known that I, ALFRED TROSCH, a citizen of the United States, and resident of Rochester, county of Monroe, State of New York, have invented an Improvement in Feed Mechanisms for Machine Tools, of which the following description, in connection with the accompanying drawings, is a specification, like characters on the drawings representing like parts in each of the several views.

This invention relates to mechanism for imparting intermittent automatic feed movement to machine tools, and more particularly to means for feeding the tool holder in the saddle or the saddle on the cross rail of a planer. In machines of this type it has been customary to derive the step-by-step movement of the tool holder or the tool saddle from a vertically extended shaft at one side of the machine, which is oscillated intermittently by suitable mechanical connections from the operating mechanism of the planer table. To impart this intermittent oscillating movement to the vertical shaft has required a mechanism of a more or less elaborate character and the object of the present invention is to eliminate this mechanism for obtaining the intermittent oscillating feed movement, by providing a magnetically operated device, operative directly on the vertical shaft to oscillate the same, this device being energized by electric current connections controlled preferably by the movement of the planer table or platen. The foregoing and other objects and advantages of the invention will be better understood from the following detailed description, taken in connection with the accompanying drawings and the distinctive features of novelty will then be pointed out in the appended claims.

Referring to the drawings:

Fig. 1 is a side elevation showing the principal portion of a planer structure with my invention embodied therein; and

Fig. 2 is a horizontal sectional detail on line 2—2 of Fig. 1.

10 indicates a planer bed, having a table 11 mounted for movement on the ways thereof. 12 indicates the vertical columns at the sides of the planer bed, on which the cross rail 14 is mounted for vertical adjustment. 17 indicates a shaft vertically mounted and journalled to extend upward alongside the

column 12, this shaft, through beveled gearing 18 and an adjustable crank connection 19, transmitting power to operate selectively the horizontal feed screw 20 and the feed shaft 21 for the vertical feed, both of which are as usual journalled in the cross rail 14. In accordance with usual practice the shaft 17 is oscillated intermittently in the operation of the machine, but only transmits a one-way movement in either direction as required, to the feed screw or feed shaft for the step-by-step feed, this one way feed movement being effected by a pawl and ratchet device or other like expedient (not shown) in the connection from the crank 19 to the feed screw and feed rod.

All the parts and connections thus far described are of ordinary and well known type and need not be further detailed herein. In accordance with my invention, the shaft 17 is equipped for magnetic actuation to oscillate the same at each movement of the planer table. For this purpose, as shown, I fix at the lower end of the shaft 17 a spur gear 22 which is engaged by a rack 23 suitably guided in a bracket 24 fixed at the side of the upright. This rack is connected with the core of a solenoid 25 which is preferably, and as shown, of a double acting type adapted to draw the core and with it the rack 23 in both directions. This double solenoid is equipped with connections to a source of electric energy 26 and with controlling means whereby it is energized to move the core alternately in opposite directions at each reciprocatory movement of the planer table. For this purpose one end of the solenoid has circuit connections 27 leading to spaced apart contacts 28 adapted to be connected by a bridging contact 29 carried at the lower end of a swinging arm 30, in one position of said arm. The other end of the solenoid has similar connections 31 with a pair of spaced contacts 32 which are bridged by the contact 29 in the other shifted position of the arm 30. The arm 30 is pivoted to the machine bed at 33 and its upper end is engaged by dogs 34 adjustably fixed to the side of the planer table 11, this rocker arm 30 and the dogs 34 being a feature of the usual equipment which has as its prime function to operate a master switch 35 which controls the driving motor of the planer table. Thus at the completion of each operative movement of the planer table one

end of the double solenoid 25 will be energized and the rack 23 thus will receive a reciprocatory movement in timed relation with the movements of the planer table as the contacts 28, 32 are successively bridged to deliver the current from the source of energy 26 alternately to the respective ends of the solenoid. Thus the shaft 17 is oscillated for a movement sufficient to feed the tool head or the tool saddle as required, the amount of this feed movement being determined by the adjustment of the transmitting crank 19. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent, is:

25. 1. A planer, comprising a work table, a tool holder mounted for movement with respect thereto, a vertical shaft mounted at one side of said table, and connected to transmit feed movement to said tool holder, a solenoid equipped for control by the movement of said work table, and connections from the core of said solenoid to said vertical shaft to actuate the same.

trol by the movement of said work table, and having a movable core, means for imparting feed movement to the tool holder, and a connection from said core to said means to actuate the same.

2. A planer, comprising a work table, a tool holder mounted for movement with respect thereto, a vertical shaft mounted at one side of said table, and connected to transmit feed movement to said tool holder, a solenoid equipped for control by the movement of said work table, and connections from the core of said solenoid to said vertical shaft to actuate the same.

3. A machine tool, comprising work moving means, a tool holder mounted for feed movement, and magnetic means connected to be controlled by said work moving means for imparting intermittent feed movement to said tool holder, said magnetic means consisting in a double solenoid equipped with connections to have the two ends thereof energized alternately by the table movement.

In testimony whereof, I have signed my name to this specification.

ALFRED TROSCH.
